UNITED STATES PATENT OFFICE.

MAX WACHSMUNDT AND ALWIN KURZ, OF BERLIN, AND CARL JACOBI, OF SÜDENDE, NEAR BERLIN, GERMANY.

APPARATUS FOR PRODUCING DEPRESSIONS IN METAL PRINTING-PLATES.

947,264.

Specification of Letters Patent. Patented Jan. 25, 1910.

Application filed August 4, 1909. Serial No. 511,120½.

To all whom it may concern:

Be it known that we, MAX WACHSMUNDT and ALWIN KURZ, both citizens of the German Empire, residing at Berlin, Prussia, 5 German Empire, and CARL JACOBI, a citizen of the German Empire, residing at Südende, near Berlin, aforesaid, have invented certain new and useful Improvements in Apparatus for Producing Depressions in Metal Printing-Plates, of which the following is a specification.

It has been attempted to produce depressions in metal printing plates, by hammering, with the assistance of special apparatus, 15 or by rolling, by means of cylinders, or by stamping entire words in one operation. All such prior apparatus, because of great drawbacks, have not led to any useful results. The hammering process has the drawback 20 that the depressions are not uniformly deep, and that the top surface is deformed by depressions etc. The same drawbacks occur in the rolling process, which has the further drawback that the stamps are easily deformed and that no accurate adjustment of 25 the words can be effected.

When simultaneously stamping several letters forming a word, it is difficult to obtain a uniform depth. Moreover, owing to the 30 great pressure required both surfaces of the plate are very easily bulged or rendered uneven, which is of great disadvantage in the printing process. We overcome these drawbacks, and also accurately adjust the depressions, and also of the stamp spindle. According to our invention, the depressions in 35 the metal plates, such as copper, steel, iron, zinc, brass etc., are not obtained, as heretofore, by engraving or by stamping entire 40 words in one operation, but separate constituent parts, such as letters, or signs (for example, music, or decorative matter) are stamped one after the other in the metal plates, in order, by thus singly making such 45 impressions, to form entire words, signs, or entire printing plates. By so doing, we have found that all deformation of the surface of the printing plate, such as bulges or unevennesses, are avoided, and that the depth of the 50 various depressions, as well as the place, at

which they are applied, can be accurately adjusted.

We are aware that stamping apparatus already exist, which enable several single depressions to be made one after the other in a 55 metal plate, but still such devices can only be used for copying, while, according to our present invention, the separate types can be combined according to desire and used for producing quite different "original" plates. 60

Our machine, which enables names etc. to be indented in printing plates, is shown in Figure 1 in plan, in Fig. 2 in side elevation, and in Fig. 3 in front elevation, while Fig. 4 shows the pressing piece in plan, Fig. 5 65 in front elevation and Fig. 6 in side elevation.

a is the base plate, which carries all the working parts of the machine and also serves as a support for the copper plate to be indented. The slide carriage *b*, which is adapted to be moved lengthwise of the base plate, by the toothed wheels *I*, engaging in the toothed racks *II*, and is guided in grooves of said base plate. Said toothed wheels *I* 70 are secured on the shaft *y*, which is journaled in the bearings *Z*. At each end of the shaft there is a slot *V*, in which a pin on a crank *VI* can engage, and by this means, the shaft can be operated from either of its ends. 75 A second, and smaller, slide or carriage *c* moves in grooves of the carriage *b*, and at right angles to the movement of the latter. A standard *d*, together with a spindle *VIII*, and fly-lever, *f*, are adapted to be moved 80 lengthwise of the slide or carriage *c*, and backward and forward, by a spindle *i*. This spindle *i* is journaled in bearings *p* and *l*, and is adapted to be turned by the hand wheel *k* through the agency of the toothed 85 wheels *X* and *j*, the latter of which is journaled in the top part of the bearing *l*. The aforesaid spindle *VIII* in the standard *d* carries at its lower end (Figs. 5 and 6), pressing piece or lining *IX*, which is held to 90 the spindle by a pin *XI* passing through a groove around the latter and through the pressing piece itself. In order to prevent the pressing piece *IX* from turning during 95 the hereinafter described stamping opera- 100

tion, a longitudinal guide is provided in the standard *d*, through which the pin *w* (Fig. 1) passes, and the lower half of the pin fits the guide hole XII (Figs. 4, 5 and 6) of 5 the pressing piece IX.

A type holder *e* in the slide *c* is kept in a perpendicular or parallel position in regard to the base plate *a* by four screws *o*, in order to assure that the type to be indented always 10 act perpendicularly on the copper plate. For the purpose of printing the names in proper position on the copper plate there is a pointer *t* inside the type holder *e*. The screw *g* provided with the screw head VII 15 passes through the screw threaded guide *h*, opens out into the slot of the type holder *e* and presses against the lining *s*. By the screw *g* the types inserted into the holder *e* are, pressed side by side, in such relation, 20 however, that they can be pressed down one at a time.

Before beginning the stamping operation, the carriage *b* is secured by the screws III and the carriage *c* by the screws *m* in order 25 to prevent these carriages from being displaced. The spring *q* (Figs. 1 and 3) is provided in order to keep the carriage *c*, at right angles while sliding on the carriage *b*. For the purpose of rendering the results of the 30 stamping operation visible, inclined openings *u* are provided in the standard *d*. At the top of the latter is secured the circular scale *r*, which, together with a pointer *v* (the latter depending from the fly lever, *f*), enables the depth of the letters to be regulated. On the scale *r* is also provided a loose pointer *x*, which to avoid mistakes is adjusted to the 35 numeral in question. The clamps IV (Figs. 1 and 2) overhang and serve to secure the 40 copper plate.

The operation of the described machine is as follows: Supposing it is desired to stamp a name at a certain point on a copper plate, the latter is placed on the base plate *a* and 45 fastened by the clamps IV. Thereafter the type holder *e* is adjusted to the point at which the stamping is to be effected the pointer, *t*, fitted within the slot of the type-holder, *e*, being above the desired point at 50 which the stamping is to be commenced, whereupon the type coming into question for the particular name are composed and put into said slot, and held in place by the screw *g*. The standard *d* is then moved so that the 55 pressing piece IX is brought exactly over the middle of said type composing said name, whereafter the spindle is screwed down and one of the type is thus pressed to the desired depth into the plate. When this has been 60 done, the spindle is screwed up again and adjusted to act on the middle of another of the type, which operation is repeated until the whole row has been printed one by one. As

soon as the name is finished the bur is ground off, and the plate is then ready for printing. 65

In order to be able to accurately adjust the point, at which the indentation has to be made in the plate, the carriage *b* can be moved along a scale XIII provided on the base plate *X*^a, a pointer XIV being provided 70 to facilitate the adjustment. Further the carriage *c* can be moved with the assistance of a second pointer XV along a second scale XVI provided on the carriage *b*. These scales XIII and XVI are disposed at an 75 angle to each other, so that an accurate adjustment of the type can be effected both longitudinally and transversely.

Instead of longitudinally and transversely adjusting the stamping device by the above 80 described means, the process can be reversed, that is to say, the stamping device may be made stationary and the metal printing plate can be adapted to be adjusted underneath the stamps. The pressure may also be exerted 85 in the opposite direction, so that, instead of the type being moved toward the plates, the plate may be moved toward the type, it being in both cases of no moment, whether the pressure between the type and the plate is effected 90 by mechanical pneumatic hydraulic or electric means.

What we claim is:

1. In an apparatus for producing depressions in metal printing plates, a base plate 95 serving as a support for a metal plate, a carriage slidable on said base-plate, a second carriage slidably carried by that first named and movable thereon at an angle to the path of travel of said first-named carriage, a type-holder on the second-mentioned carriage, a standard supported by said second-named carriage and slidable thereon, a spindle carried by the standard, and a pressing piece on the spindle and adapted to press against 105 type, when in said holder, against a metal plate when supported by the base plate.

2. In an apparatus for producing depressions in metal printing-plates, a carriage provided with a type-holder, a standard carried by and slidable on said carriage, a spindle carried by the standard and adapted to 110 press against type, when in said holder against a metal plate.

3. In an apparatus for producing depressions in metal printing-plates, a standard, a plate carried thereby and bearing a scale, a loose pointer movable relatively to said scale, a spindle in the standard, a fly-lever for moving said spindle in said standard, and a second pointer carried by the spindle and movable 120 relatively to the scale and independently of the first-mentioned pointer.

4. In an apparatus for producing depressions in metal printing-plates, a base-plate 125 bearing a scale, a carriage movable thereon

and also bearing a scale, a pointer carried by the carriage for indicating markings on the first-named scale, a second carriage movable at an angle to the path of that first named, 5 and a pointer carried by said second carriage for indicating markings on the second named scale.

In witness whereof we have hereunto set

our hands in the presence of two subscribing witnesses.

MAX WACHSMUNDT.
ALWIN KURZ.
CARL JACOBI.
